UNITED STATES PATENT OFFICE.

JOSEPH GELINAS, OF ST. BARNABÉ, QUEBEC, CANADA.

DESIGN FOR A TRACE-HOOK.

43,529.

Specification for Design.

Patented Feb. 11, 1913.

Application filed November 8, 1912. Serial No. 730,267. Term of patent 14 years.

To all whom it may concern:

Be it known that I, JOSEPH GELINAS, a subject of the King of Great Britain, residing at St. Barnabé, Province of Quebec, Canada, have invented a new, original, and ornamental Design for Trace-Hooks, of which the following is a specification, reference being had to the accompanying drawings, forming part thereof.

Figure 1 is a plan view of the trace hook, and Fig. 2 is a side elevation.

I claim:

The ornamental design for a trace hook, as shown.

JOS. GELINAS.

Witnesses:

T. L. PIDGEON,
ADEM GELINAS.
